DESIGN FOR A WEDDING RING GUARD OR SIMILAR ARTICLE

Harold James Damptz, Chicago, Ill.

Application April 4, 1947, Serial No. 138,156

Term of patent 7 years
(Cl. D45—10)

To all whom it may concern:

Be it known that I, Harold J. Damptz, a citizen of the United States, and residing in the city of Chicago, in the county of Cook and State of Illinois, have invented a new, original, and ornamental Design for a Wedding Ring Guard or Similar Article, of which the following is the specification, reference being had to the accompanying drawings, forming a part thereof.

On the drawings:

Fig. 1 is a side elevational view of a wedding ring guard showing my new design;

Fig. 2 is a perspective view of the guard;

Fig. 3 is another side elevational view thereof from that shown in Fig. 1; and

Fig. 4 is a top plan view of the wedding ring guard, portions thereof being broken away for purposes of illustration.

I claim:

The ornamental design for a wedding ring guard or similar article, substantially as shown.

HAROLD JAMES DAMPTZ.
